(57) **CLAIM**

We claim the ornamental design for an attachable light for books or the like, as shown and described.

DESCRIPTION

FIG. 1 is a front perspective view of an attachable light for books or the like showing our new design;

FIG. 2 is a rear perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a left side elevational view thereof; and,

FIG. 8 is a right side elevational view thereof.

The broken lines represent portions of the light which form no part of the claimed design.
